[57] CLAIM

The ornamental design for a video game controller, as
shown and described.

DESCRIPTION

FIG. 1 is a right side elevational view of a video game
controller showing my new design;
FIG. 2 is a left side elevational view thereof;
FIG. 3 is a rear elevational view thereof; and,
FIG. 4 is a top plan view thereof.
The bottom is plain and unornamented.

FIG - 1

FIG - 2

FIG - 3

FIG - 4
